UNITED STATES PATENT OFFICE.

GEORGE F. GOELZ, OF WEST NEW YORK, NEW JERSEY.

CLOTHES-LINE SUPPORTING AND MANIPULATING APPARATUS.

1,122,906.

Specification of Letters Patent.

Patented Dec. 29, 1914.

Application filed March 12, 1914. Serial No. 824,093.

To all whom it may concern:

Be it known that I, GEORGE F. GOELZ, a citizen of the United States, and residing at West New York, in the county of Hudson and State of New Jersey, have invented certain new and useful Improvements in Clothes-Line Supporting and Manipulating Apparatus, of which the following is a specification, such as will enable those skilled in the art to which it appertains to make and use the same.

This invention relates to clothes lines and supports thereof, and particularly to what are known as window attachments or supports for lines of this class, and which are used in connection with a pole or other supplemental support at a predetermined point or distance from the window, and which is provided with a pulley around which the line is passed, and the object of this invention is to provide a window attachment of the class specified involving a pivotally supported arm which is provided with a pulley around which the line is passed, and which may be swung inwardly through the window into a room or compartment from which the line may be conveniently manipulated in the operation of placing laundry articles thereon to dry, said arm being adapted to be swung downwardly and out of the window to permit the closing of the sash or sashes, after the articles to be laundered have been placed on the line, and with this and other objects in view, the invention consists in a device of the class specified constructed and operating as hereinafter described and claimed.

The invention is fully disclosed in the following specification of which the accompanying drawing forms a part, in which the separate parts of my improvement are designated by suitable reference characters in each of the views, and in which:

Figure 1 is a vertical section of a window provided with my improvement;—Fig. 2 a partial horizontal section thereof;—Fig. 3 a plan view of an arm supporting sleeve which I employ, and Fig. 4 a face or outside view of a bracket attachment which I employ, detached and which is shown in use in Fig. 1 and in use and in section in Fig. 2.

In the drawing forming part of this specification, I have shown at *a*, in Fig. 1, one side portion of a window or frame in which is mounted top and bottom sashes *b* and *c*,

the bottom sash *c* being shown in a raised position.

In the practice of my invention, I provide a bracket attachment *d* which is adapted to be secured to the outer face or surface of the side *a* of the window frame, and which is provided with a central tubular bearing *d*² provided at one end with clutch lugs or projections *d*³ which are preferably four in number.

The central tubular bearing *d*² is threaded on its inner side and I also provide a bolt *e* having at one end a milled or other head *e*², and the opposite end *e*³ of which is threaded to correspond with the thread in the tubular bearing *d*², and mounted on the bolt *e* is a sleeve *f* provided centrally of one side with a threaded coupling *f*² into which is screwed a tube or rod *g* which constitutes the folding or swinging arm of my attachment.

The sleeve *f* is provided at its inner end with a plurality of clutch notches or recesses *f*³ which correspond with the lugs or projections *d*³ on the tubular bearing *d*², and when the sleeve *f* is not locked in connection with the tubular bearing *d*², it is free to rotate on the bolt *e*.

The arm *g* is provided at its free end with an elbow attachment *h* with which is connected a pulley block *i* through which the line *j* is passed, and in practice, the line *j* is also passed through another pulley block mounted on, or connected with a supplemental support at a predetermined distance from the window, as hereinbefore set out, said supplemental support being not shown.

The elbow attachment *h* is preferably tubular in form and screwed into the end thereof is a headed plug *k*, and the block *i* is provided with a ring or staple *i*² through which said plug is passed, and which is free to rotate on said plug.

In the construction shown in Fig. 2, the bolt *e* is screwed home and the sleeve *f* is locked against rotation, and when it is desired that the sleeve *f* and arm *g* rotate on said bolt, the latter is turned to the left, with the construction shown, and partially withdrawn from the bearing *d*² and this operation permits the sleeve *f* to move or be moved outwardly, and thus disengaged from the bearing *d*², at which time the arm *g* may be swung into any desired position.

When the line *j* is not in use, both parts

thereof are placed over the bolt *e* or sleeve *f* between said arm and the head *e*² of said bolt, and the arm *g* is swung downwardly into the position shown in dotted lines in Fig. 1, in which position the sashes *b* and *c* may be manipulated in the usual or any desired manner. When it is desired to place laundry articles on the line *j*, the sashes *b* and *c* are both raised, as shown in Fig. 1, and the arms *g* swung inwardly and locked in the position shown in said figure, and the laundry articles may be placed on the line *j*, as will be readily understood, by a party standing in the room or compartment within the window, and when all the articles have been placed on the line, both parts thereof are raised and passed over the outer end portion of the bolt *e*, after which the sleeve *f* and the arm *g* are swung downwardly into the position shown in dotted lines, and when it is desired to remove the laundry articles from the line, the above operation is repeated, or the arm *g* is raised into the position shown in full lines in Fig. 1.

My invention is not limited to any exact means for connecting the pulley block *i* with the arm *j*, except that, when in use, the said pulley block must be supported partially with said arm to permit of the opera-

tion or manipulation of the line *g* as herein set out, and changes in and modifications of the construction herein described may be made within the scope of the appended claim, without departing from the spirit 35 of my invention or sacrificing its advantages.

Having fully described my invention what I claim as new and desire to secure by Letters Patent is:—

A line supporting attachment of the class described comprising a bracket adapted to be secured to a window frame and provided with a tubular bearing, a bolt one end of which is threaded and adapted to be 45 screwed into said bearing, and the other end of which is provided with a head, a sleeve rotatably and slidably mounted on said bolt and an arm connected with said sleeve, said sleeve and said bearing being 50 provided with clutch members.

In testimony that I claim the foregoing as my invention I have signed my name in presence of the subscribing witnesses this 11th day of March, 1914.

GEORGE F. GOELZ.
